UNITED STATES PATENT OFFICE.

HERBERT T. BRADLEY, OF DETROIT, MICHIGAN.

CASH-REGISTER.

SPECIFICATION forming part of Letters Patent No. 434,374, dated August 12, 1890.

Application filed January 11, 1890. Serial No. 336,612. (No model.)

To all whom it may concern:

Be it known that I, HERBERT T. BRADLEY, a citizen of the United States, residing at Detroit, county of Wayne, State of Michigan, 5 have invented a certain new and useful Improvement in Cash Registers and Indicators; and I declare the following to be a full, clear, and exact description of the invention, such as will enable others skilled in the art to 10 which it pertains to make and use the same, reference being had to the accompanying drawings, which form a part of this specification.

My invention is designed to produce a cash 15 register and indicator which shall be positive in its operation and yet simple in construction; and it consists of a combination of devices and appliances hereinafter described and claimed.

20 In the drawings, Figure 1 is a perspective view of the exterior of my machine. Fig. 2 is a vertical section of the same. Fig. 3 is a horizontal section with the parts in elevation. Fig. 4 is an elevation of the key-table. Fig. 25 5 illustrates the mechanism for operating the table. Fig. 6 is a perspective view illustrating a portion of the mechanism; and Fig. 7 is a detail perspective view of the arms for operating the table or carriage by sliding the 30 drawer.

In carrying out my invention, A represents the case of my machine.

B is a series of operating-keys adapted to be struck by the operator in recording a sale. 35 Each key represents one of the digits, and there is also a key for the 0. Each key has a shank b, which extends down into the case, the lower end entering and playing in the bar B', which extends across the machine. 40 The keys are thus supported so that they can have a free vertical movement.

C are levers extending from front to rear of the case and supported by the bar C', which extends across. To the front end of each of 45 the levers C is pivoted one of the keys, as at b', the engagement being such that as the key is struck the rear end of the lever will be thrown up. On this rear end is a transverse slot or opening c.

50 D is what may be termed a movable "table" or "carriage," and on this table or carriage the recording type-levers E are mounted.

These type-levers are preferably shaped, as shown in Fig. 2, in the form of a bell-crank, and are pivoted to the table or carriage at e. 55 The lower or short arm e' extends down and enters the slot c. On the end of the upper or long arm e² is the projection e³, containing a recording-type corresponding with the figure on the corresponding actuating-key B. These 60 type-levers E are all set at such an angle that when actuated the projection e³ of each type-lever will pass through the orifice d of the table or carriage.

F is a roll of paper, and G is a roll on which 65 the paper is wound after the recording has been done. Between the two is what may be termed a "stationary platen" H. The projection passing through the orifice, the type strikes the paper and records the figure. 70

d' is an inking-roller mounted on the spring d² and adapted to ink the type just before it strikes the paper.

I will now describe the mechanism whereby a motion is imparted to the table or carriage. 75 I is a universal bar extending across the machine underneath the levers C and back to the rear of the machine. This bar is pivoted at i. J is a wheel or drum pivoted to the table or carriage D and provided with the 80 spring J'. J² is a rack-bar attached to the case. A portion of the periphery of the drum or wheel J is provided with the teeth j, adapted to mesh with those on the rack-bar, while the balance is provided with the ratch- 85 et-teeth j'. J³ is an escapement-lever pivoted at j² to the table. This escapement-lever is connected by the rod J⁴ with the rear end i' of the bar I, and the construction is such that the raising of the rear end of the bar I 90 operates the escapement-lever J³, so that the pawl j³ on the lower end engages in the ratchets and prevents the revolution of the wheel. Then when the bar I is lowered the wheel or 95 drum J, through the spring J', will be re-volved until the upper end j⁴ engages in the next ratchet-tooth. The pawls j³ j⁴ may be pivoted on the escapement-lever J³ to render them more capable of engaging and releasing the ratchet; but the pivoting of the pawls is 100 not indispensable. The wheel meshing with the rack-bar will thus move the table the space of one ratchet each time the front end of the bar I is depressed, or, in other words,

each time a key is struck. Thus if the operator wishes to record a sale of twenty-five dollars and thirty-seven cents he strikes first key No. 2. This operates, through the lever 5 C and key E, to record on the paper ribbon the figure 2, and when the actuating-key is released the table, through the medium of the rack-bar J², wheel J, and spring J', is moved along one space, ready for the figure 5 to be 10 recorded, and so on until all four figures have been recorded.

I will now describe the mechanism for moving the paper: K is a bar extending from front to rear of the machine, the front end 15 pivoted at k to the end of the universal bar I, while the bar is fulcrumed at k', being movable horizontally on this fulcrum. A spring k² serves to keep the bar in the position shown in Fig. 3 until moved by exterior 20 means. K' is an arm or rod extending down from the carriage or table adjacent to the bar K, so that as the table moves to the right when the key is released it carries the bar K with it. L is a vertical rod supported at l, 25 the lower end being in such position that as the bar K is forced to the right by the table or carriage it will be under the end of the rod L after the key for the next to the last figure is struck and released, as illustrated in Fig. 30 6. Now when the last key is struck the depression of the front end of the bar K acts to force up the vertical rod L. M is a small pivoted lever or pawl having the pivoted segment m on its end. M' is a ratchet-wheel 35 keyed to the shaft of the drum on which the paper is wound. Now when the last key is struck, as before explained, and the rod L raised, it presses against the lever M and drops the segment m down under the next 40 tooth. Then the release of the key and lowering of the rod allows the spring M² to bear on the lever M and move the wheel one space. This moves the paper up opposite an opening in the case, so that it can be seen from 45 the exterior, and by placing the lens M³ in the case the figures will be enlarged, so that they can be plainly seen. The segment m is pivoted and arranged as shown to enable it to yield and move down past one of the teeth 50 of the ratchet-wheel M', so as to be placed under such tooth for turning the ratchet-wheel one tooth when the rod L descends.

I will now describe the mechanism for operating the cash-drawer and for returning the 55 table or carriage to its normal position after a sale has been recorded. N represents the drawer, and N' is a spring placed behind it for throwing it out when released. O is a small latch pivoted to the case, having on its 60 under side a beveled projection o, adapted to engage in a notch on the side of the drawer. The side of this latch also has a projection O', under which the bar K is forced by the last movement of the table or carriage, as 65 shown in Figs. 3 and 6. Thus the striking of the last key operates to raise the latch O and release the drawer, which is forced open by

the spring. P is an arm extending from the side of the case above the drawer and supports on its outer end a vertical pivot. Keyed 70 to the upper end of this pivot is the arm P', adapted to bear on the arm or rod K', which is attached to the table, and keyed to the lower end is the arm P², extending horizontally to the edge of the drawer. P³ is a pin or projection 75 on the drawer adapted to strike the arm P². As the drawer is thrown out, this pin or projection strikes the arm P² and revolves it until it has passed, when the spring p throws it around until the arm P' bears on the rod K'. Now as the drawer is closed this pin or projection, bearing on the arm P², causes the arm P' to move the table back until the pin has cleared the arm P². The table is thus 80 thrown over ready to have another sale recorded, and the spring k² serves to return the rod K to its normal position.

I have heretofore explained the manner of recording a sale the amount of which contains four figures. In order to provide for 90 recording a sale of less than four figures, the space-key B² is provided. This key makes no record, but simply acts on the universal bar and moves the table. Thus if one dollar and 95 eighty-eight cents are to be recorded the operator strikes the space-key first, then 1, 8, 8; if twenty-five cents, he strikes the space-key twice, then 2, 5; if seven cents, he strikes the space-key three times, then 7.

What I claim is—

1. In a cash-register, the combination of a traveling carriage, a series of type-levers pivotally mounted on the carriage, key-levers for operating the type-levers, a stationary rack-bar, a spring-driven ratchet-drum having 105 teeth engaging the rack and journaled on the carriage, an oscillatory escapement-lever engaging the ratchet part of the drum to hold and release the latter, a vibrating universal bar common to all the key-levers and operated by any one thereof, and a rod-connection between the universal bar and the escapement-lever to oscillate the latter, substantially as described.

2. In a cash-register, the combination of a 115 casing having a sight-opening in its upper portion, a platen arranged in the casing in alignment with the sight-opening, and drums or rollers for supporting and moving the record-strip vertically against the platen between 120 the latter and the sight-opening, with key-levers at the base part of the casing, a traveling carriage within the casing, type-levers pivoted on and traveling with the carriage, and means for operating the type-levers, moving 125 the carriage, and actuating the drums or rollers by the movement of the key-levers, substantially as described.

3. In a cash-register, the combination of a 130 casing containing a platen, drums or rollers for supporting and moving a record-strip over the platen, a traveling carriage, a series of type-levers pivoted on the carriage, key-levers for operating the type-levers, a rack-bar, a

spring-driven ratchet-drum having teeth engaging the rack-bar and journaled on the carriage, a lever pivoted on the carriage for holding and releasing the spring-drum, a vibrating universal bar actuated by any one of the key-levers and serving to operate the lever which holds and releases the drum, and means for rotating one of the strip-supporting drums or rollers by the depression of a key-lever to move the record-strip over the platen, substantially as described.

4. In a cash-register, the combination, with a stationary platen and drums or rollers for supporting and moving a record-strip over the platen, of a traveling carriage, type-levers pivoted on the carriage, movable key-levers, and means operated by the key-levers to feed the carriage, actuate the type-levers, and rotate one of the strip-supporting drums or rollers, substantially as described.

5. In a cash-register, the combination of a traveling carriage, type-levers pivoted on the carriage, a rack-bar, a spring-driven ratchet, a spring-drum having teeth engaging the rack-bar and journaled on the carriage, a lever pivoted on the carriage and engaging the ratchet part of the drum for holding and releasing the latter, movable key-levers, and devices operated by the key-levers to actuate the type-levers and operate the drum holding and releasing lever, substantially as described.

6. In a cash-register, the combination of a stationary platen, drums or rollers for supporting and moving a record-strip over the platen, a traveling carriage, type-levers pivoted on the carriage, a spring-driven drum journaled on the carriage, means for moving the carriage as the drum rotates, a lever pivoted on the carriage and engaging the drum to hold and release the latter, movable key-levers, and means operated by the key-levers to actuate the type-levers, the drum holding and releasing lever, and one of the strip-supporting drums or rollers, substantially as described.

7. In a cash-register, the combination of a platen, rotating drums or rollers for supporting and moving a record-strip across the platen, a traveling carriage, type-levers pivoted on the carriage, a rack-bar, a spring-driven ratchet-drum having teeth engaging the spring-drum, a lever pivoted on the carriage and engaging the ratchet part of the drum to hold and release the latter, movable key-levers connected with and serving to operate the type-levers, a universal bar arranged beneath and depressed by any one of the key-levers, a connection between the spring-drum holding and releasing lever and the universal bar, and means operated by the

latter to rotate one of the strip-supporting drums or rollers, substantially as described.

8. In a cash-register, the combination of a platen, a traveling carriage, type-levers pivoted on the carriage, a record-strip-supporting device, key-levers for operating the type-levers, a universal bar extending beneath the key-levers and operated by any one thereof, the pivoted lever K, having its outer end pivotally connected with the universal bar and its inner end movable horizontally, and the vertically-movable rod L, operated by said pivoted lever for actuating the strip-supporting device to move the record-strip across the platen, substantially as described.

9. In a cash-register, the combination, with a horizontally-moving table, type-levers pivoted thereon, a movable strip-supporting drum or roller, and a series of key-levers for operating said type-levers, of a universal bar extending beneath the key-levers and adapted to be operated by any one thereof, the pivoted lever K, having its outer end pivoted to the universal bar and its inner end adapted to move horizontally, the spring k^2 for keeping the inner end of the lever K adjacent to the carriage, the vertically-moving rod L, adapted to be moved by the end of the lever K, and mechanism connecting the upper end of the rod L with the strip-supporting drum or roller, substantially as described.

10. In a cash-register, the combination, with the key-levers C, a universal bar extending beneath the same and adapted to be operated by any one of the levers, the lever K, having its outer end pivoted to the universal bar, and mechanism for moving the inner end of the lever K laterally as each key is struck, of the cash-drawer, the latch O, adapted to engage the drawer and formed with the projection O' for engaging the lever K when the latter is forced adjacent to the latch, and the spring N', adapted to force out the drawer when the latch is raised and the drawer released, substantially as described.

11. In a cash-register, the combination, with a traveling carriage, type-levers pivoted thereon, key-levers connected with the type-levers, and means for moving the carriage by the key-levers, of a cash-drawer having a projection P³, and mechanism for returning the carriage to its normal position when the drawer is closed, consisting of a pivot P, having arms P' P², substantially as described.

In testimony whereof I sign this specification in the presence of two witnesses.

HERBERT T. BRADLEY.
